MANUFACTURING COMPANY, OF MILWAUKEE, WISCONSIN, A CORPORATION
OF DELAWARE.

ENGINE-STARTING DEVICE.

1,245,464.

Specification of Letters Patent.

Patented Nov. 6, 1917.

Application filed December 22, 1913. Serial No. 808,907.

To all whom it may concern:

Be it known that JOHN J. KANE, a citizen of the United States, residing at Milwaukee, in the county of Milwaukee and State of Wisconsin, has invented a certain new and useful Improvement in Engine-Starting Devices, of which the following is a specification.

This invention relates in general to devices for aiding in or accomplishing the starting of internal combustion engines, and has particular relation to such devices as are of use in starting the engines of motor vehicles.

15 The object of the invention is to provide an improved starter of comparatively simple design that surely and efficiently accomplishes the starting of an internal combustion engine.

20 A further object is to provide a starting device that need present to the operator no other control devices than are necessary for the actual control of the engine and vehicle, or other driven mechanism, the starting device being actuated or controlled by the engine or vehicle controlling apparatus.

A further object is to provide an improved starting device and means for actuating the same, that are incapable of being actuated 30 when the engine is running under normal conditions at a speed above a predetermined value.

35 A further object is to provide an improved starting device actuated by an electrically driven motor, coupled to the engine by an improved power transmitting means that insures that no damage will occur to the motor when the engine is started and running under its own power.

40 A further object is to provide an improved starting device embodying the same dynamo-electric machine that acts, at times, to produce current for various purposes, and insuring the proper operation of this machine, 45 at all times, as a generator or a motor.

These and other objects are attained by this invention, the various novel features of which will appear from the description and drawing forming part of this application, which discloses one embodiment of such invention, and will be particularly pointed out in the claims.

In the accompanying drawings:

Figure 1 is a diagrammatic view of an en-

gine starting device embodying the invention, certain parts being shown in section, and the initial operating mechanism being shown in perspective.

Fig. 2 is a similar view, showing a modification of the device of Fig. 1, embodying means for insuring successive operation of different elements of the starting device.

Fig. 3 is a diagrammatic view illustrating a modification of the apparatus shown in Figs. 1 and 2.

As shown in Fig. 1, an engine 4, has a fly-wheel 5 and a gear 6, fixed to the crank shaft 7. A clutch 8, slidable on and keyed to a shaft 9, and urged into position by a spring 13 to effectively clutch a portion of the fly-wheel 5, is adapted to transmit power from the engine to a transmission or work shaft 10, through gears 11 and 12 on the shafts 9 and 10, respectively. The clutch 8 is adapted to be disengaged from the fly-wheel 5 by means of a bell crank lever 14, operated through a connecting rod 15 by a crank 16, mounted on a shaft 17. Power for operating crank 16 may be efficiently applied through an arm or pedal 18 integral with said crank. This crank is provided with an integral extension 19, for a purpose to be hereinafter described.

A dynamo-electric machine M, capable of use as either a generator or motor, has its rotary part mounted on a shaft 21. This machine, in the form shown, is provided with both a series field winding 22 and a shunt field winding 23; although, as is obvious, any machine capable of operation as a generator and motor might be used. In the preferred operation of the starting device of this invention, the dynamo-electric machine M is connected to a battery B, which supplies energy for operating the machine as a series motor to start the engine; and, when the engine is up to speed and operating under its own power, the machine M is adapted to operate as a shunt wound generator for feeding the battery B. A switch S is provided for the purpose of establishing the desired connections between the motor-generator M and the battery B. This switch may be of any type suitable for the purpose, and is shown as comprising three separate bridging portions S_a, S_b and S_c, adapted to bridge the shunt field terminal 23_a and battery terminal B_a, shunt field

terminal 23_b or series field terminal 22_a and armature terminal M_a, and series field terminal 22_b or armature terminal M_b and battery terminal B_b, respectively. The switch 5 S, in one position, properly connects the motor generator for operation as a series generator supplied with energy from the battery B, and, in another position, connects the motor-generator as a shunt wound generator for feeding the battery B.

10 A gear 24 is mounted on the motor shaft 21 so as to be capable of rotation relatively to said shaft, and meshes with the gear 6 on the crank shaft 7. A clutch 25, keyed to 15 and slidable on the motor shaft 21, is adapted to engage with a portion of the gear 24, to establish a driving connection between the motor shaft and said gear. A pinion 26 is also secured to the motor shaft.

20 Mounted on an intermediate shaft 27, suitably positioned adjacent both the motor shaft and the crank shaft, is a one-way driving clutch 28. This clutch is loose on the shaft 27 and capable of axial movement 25 thereon. The clutch comprises two parts, one part 29 being provided with gear teeth to mesh with the motor pinion 26, and the other part 30 having a pinion 31, integral with or secured thereto and adapted to mesh 30 with gear teeth 32 formed on the periphery of a portion of the fly-wheel 5. This one-way clutch 28, may be of any suitable general type, and is here shown as one in which the parts are axially movable together and 35 such that when the part 29 is driven by the motor pinion 26, a driving connection with the part 30 is made. In the type illustrated the part 29 is mounted to rotate on an integral extension of the part 30 and is held 40 against axial movement relatively thereto by a collar 33 on said extension. As illustrated, the gear part 29 is always in mesh with the pinion 26 on the motor shaft, but as will be obvious, the part 29 may be normally out of 45 mesh with the pinion 26, and may be moved into mesh therewith by the same operation that meshes the pinion 31 with the gear teeth 32 on the fly-wheel, as these parts are mounted for axial movement together.

50 The clutch 25 is operated by a lever 36 and the clutch 28 is operated by a lever 37. The lever 36 is connected to the operating rod 38 of the switch S, and the lever 37 is connected to a rod 39, both operating rods 55 38 and 39 being connected to a bell crank lever 41. The lever 41 is actuated through a rod 42 by a crank 43. This crank 43 may conveniently be loosely mounted on the shaft 17, although any construction that will permit, at times, the operation of the crank 43 when the crank 16 is operated, will suffice. In the construction illustrated, the crank 43 is provided with an electro-magnet 44, the core 45 of which is, in the unenergized condition of the magnet, extended by

a spring or otherwise, into the path of the projection 19 of the crank 16.

It is desirable that the crank 43 be operated to actuate the levers 36 and 37 of the switch S through the bell crank 41, only when the engine is to be started. One way of accomplishing this result is to have the circuit of the magnet 44 completed only when the engine is running and to withdraw the extending core 45 of the magnet 75 44 from the path of the projection 19 on the crank 16 when the engine is started and is driving the dynamo-electric machine M as a generator.

As shown, one side of a circuit 47, which 80 supplies the magnet 44, is connected through a circuit 49 to one of the terminals of the machine M, and the other side of this circuit 47 is connected through a circuit 51, terminal 23_a, switch contact S_a, terminal 85 B_a, and circuit 52 to the other terminal of the machine M. It will be obvious from these connections that it will be impossible to complete the circuit of the magnet 44 except when the switch S is in generator position, and current flows in this circuit only when the machine M is operating as a generator and furnishing such current.

An electro-magnetically operated switch 53 is provided which prevents the connection 95 of the machine M, as a generator, to the battery B to charge the same, except when the voltage of the machine is above a predetermined value. This switch will prevent the backward flow of current when the generator voltage is lower than the voltage across the battery terminals.

With the parts in the positions as shown in Fig. 1, the engine is at rest and the motor-generator is connected as a generator, but 105 the circuit to the battery is open at the switch 53. The circuit of the magnet 44 is connected to the machine terminals, but as the machine is inoperative to develop current, the core 45 is in its extended position, 110 in the path of the projection 19 on crank 16. If the pedal or arm 18 is moved in a clockwise direction, the clutch 8 is disengaged and the crank 43 is actuated through the engagement of the projection 19 with the core 115 45, thus actuating the bell crank lever 41, which in turn releases the clutch 25 to disconnect the gear 24 from the motor shaft and actuates the lever 37 to mesh the pinion part 31 with the gear teeth 32 on the periphery of the fly-wheel 5. The same operation of the bell crank 41 actuates the switch S to establish connections between the motor-generator M and the battery B, such that machine M operates as a series motor supplied with energy by the battery. As the one-way clutch 28 is such that when the part 31 is driven by the pinion 26 the part 30 is operated, and as the mechanical transmission between the motor M and the crank 120 11

shaft 7 is such as to produce a considerable speed reduction, the engine is started in operation at a considerably reduced speed.

When the engine is operating under its own power, the speed of the crank shaft is considerably greater than when the same was driven by the motor M, and, consequently, there is a tendency to rotate the motor shaft at a greatly increased speed.

10 This, however, is prevented by the one-way clutch 28 which prevents the part 30 from driving back on the motor pinion, and as the part 29 runs loose relatively to the part 30, no harm can be done if the parts of the starting device are left in engine starting position for a considerable length of time.

When it is apparent that the engine is operating under its own power, which usually occurs before the crank shaft has made 20 three or four rotations, the pedal 18 is relieved of pressure and is returned to its original position by the spring 13 acting through the bell crank 14 and connecting rod 15. This same action of the spring 13 forces the clutch 8 into engagement with the clutch portion of the fly-wheel and connects the work shaft 10 so as to be driven by the engine. As the pressure of the crank 16 is removed from the core extension 45 of 25 the crank 43, the spring 40, acting through the connecting rod 42, returns the crank 43 to its original position and operates the bell crank lever 41 to move the pinion part 31 of the clutch 28 out of engagement with the gear teeth 32 on the fly-wheel, and also 30 operates the clutch 25 to connect the gear 24 with the motor shaft, the same being now driven from the crank shaft through the meshed gears 6 and 24. This same actuation 35 of the lever 41 operates the switch S to change the connections between the motor-generator and the battery so that the motor-generator now operates as a shunt wound generator. If the voltage developed at the 40 generator terminals is sufficient, the switch 45 53 is closed and the generator acts to charge the battery B.

When the switch S is operated to establish generator connections, the magnet 44 is 50 energized by current from the generator to withdraw the core extension 45 from the path of the projection 19 on the crank 16, so that the clutch 8 may be operated at any time, as for shifting gears or any other purpose, while the engine is running—that is, above a speed sufficient to develop the voltage necessary to energize the magnet 44 to cause retraction of the core extension 45—without operating any of the parts of the 55 starting device.

In Fig. 2 is shown a modification of the invention disclosed in Fig. 1, wherein the most efficient operation of the starting device on the engine is secured. The mechanical transmission between the motor-genera-

tor and the engine for establishing starting and driving connections between the same, as shown in this figure, effects, successively, 70 operation of the switch S, to start the machine M as a motor, the meshing of the intermediate gear with the gear teeth on the fly-wheel, and, finally, the establishment of a driving connection between the motor and the engine.

Instead of a clutch 28, with all its parts 75 movable together on a shaft to establish driving connections between the motor and engine, as shown in Fig. 1, a clutch 61, having its parts relatively movable and operating at different times, is provided. One 80 means for securing these successive operations comprises the relatively movable clutch parts 62 and 63, the latter being, of itself, a one-way driving clutch, and both being 85 loosely mounted and capable of only a limited separation on a shaft 64 slidable in suitable bearings. The parts 63 and 62 are normally held spaced apart by a spring 65 and collars 66 are provided on the shaft 64 to limit the degree of separation. The part 62 90 is provided with a pinion portion 67 integral therewith or attached thereto to mesh with gear teeth 32 on the fly-wheel 5, and the part 63 is provided with a portion 68 having gear teeth adapted to mesh with the 95 pinion 26 on the motor shaft. With the construction shown, both movement of the two clutch parts, as a unit, and relative movement between the two parts may be secured by providing a fixed abutment 69 with which 100 the pinion clutch part 62 engages to limit its movement. When this limit of movement is reached, relative movement between the two clutch parts may be secured to operatively 105 clutch the parts together.

The desired operation of the parts may be secured by operatively connecting the shaft 64 to a lever 37, so that when force is exerted on said lever, this force will be transmitted through the shaft 64 and right 110 hand collar to the clutch part 63 and, through the spring 65, to the other clutch part 62. The initial movement may be utilized for meshing the gear portion 68 with the pinion 26 and the pinion portion 67 with 115 the gear teeth 32. When the gear portion 68 is meshed with the pinion 26 and the pinion portion 67 is fully meshed with gear teeth 32, the part 62 will have engaged an abutment 69 to limit further movement of 120 such part. Continued operation of the lever 37 in the same direction will force the clutch part 63 into engagement with the clutch part 62 against the action of the spring 65. The clutch parts 62 and 63 may 125 be so disposed relatively to the pinion 26 and the fly-wheel 5, that the initial operation of the lever 37 meshes the gear part 68 with pinion 26, further operation meshes the pinion portion 67 with the gear teeth 32, and 130

continued operation finally clutches the parts 62 and 63.

It will be obvious that other methods of effecting the successive operation of the clutch parts 62 and 63 can be used, as, for instance, the shaft 64 might be fixed against axial movement and the lever 37 might be so connected as to actuate the clutch part 63 directly and the clutch part 62 indirectly, the separation of the clutch parts being limited in any suitable way.

The lever 37 is operatively connected to the bell crank lever 41 through the connecting rod 39, and the lever 36 for operating the clutch 25, is connected to the bell crank lever 41 through the operating rod 38 of lever 41 through the operating rod 38 of the switch S. As in Fig. 1, the bell crank lever 41 is actuated by the crank 43 through the connecting rod 42.

It is obvious that the most effective turning of the engine shaft is obtained when the motor is operating at full speed. As a means for providing such a time interval as will allow the motor to attain full speed before the same is operatively connected to the engine shaft, a dashpot 71 is so secured in position that the connecting rod 42 operates through the same. The rod 42 may be provided with a piston 73 having openings 74 closed on the inner side by a valve 75 to allow an unretarded movement of the piston in one direction. A stop 76 on the rod 42 limits the opening movement of the valve 75. The outer or open end of the dash-pot is provided with elongated openings 77 which allow an unretarded initial movement of the piston in its cylinder. The back end of the cylinder may be provided with a leak opening 78. Ports 79 and 80, of appreciable size, are provided at the inner end of the dash-pot cylinder, and a passage 81 in the wall of the cylinder, or adjacent thereto, connects these ports. The openings 77 do not extend as far as the ports 79, thus leaving an unperforated portion of the dash-pot cylinder, which construction necessitates a retarded movement of the piston over this portion, as the only outlet is the leak opening 78. It will be obvious that when the piston uncovers the port 79, unretarded motion of the piston may be had to the end of its stroke. This construction gives, successively, an unretarded motion, a retarded motion and an unretarded motion to the connecting rod 41 and the parts connected therewith.

Instead of furnishing the magnet 44 with current from the dynamo-electric machine, when the same is acting as a generator, this magnet may be connected directly to the battery terminals, and a switch 82 may be provided to close the supply circuit 84 of magnet 44 as soon as the machine, acting as a generator, produces any appreciable current. In this way it will be possible to have

a maximum amount of power acting on the core 45 to hold the same withdrawn, as long as the generator is producing any appreciable energy.

A circuit 85, controlled by a switch 86, 70 may be used, in connection with one side of the supply circuit 84, to supply the magnet 44 with energy from the battery, whether the machine M is operating or not. This arrangement may be useful at times when any 75 part of the starting device is out of order, or whenever it is desirable to utilize some other means, as an ordinary crank, for starting the engine. It will be obvious that with the switch closed, the core 45 will be withdrawn from the path of the projection 19. As will be apparent, the apparatus illustrated in Fig. 1, may also be provided with an auxiliary circuit for energizing the magnet 44.

When the parts are in the positions shown in Fig. 2 and the engine is at rest, on the operation of the pedal 18 in a clockwise direction, the clutch 8 is disengaged and the crank 43 is operated through engagement 90 of the projection 19 with the core extension 45. The first part of the movement of the pedal 18 and its associated parts will be unretarded, due to the openings 77 in the dash-pot cylinder, and the bell crank 41 will be 95 actuated to move the switch S to the position in which the machine M is connected to the battery as a series motor. This same movement of the bell crank 41 will slide the clutch parts 62 and 63 and the shaft 64 100 to mesh the gear part 68 with the motor pinion 26, and to mesh the pinion portion 67 with the gear teeth 32 on the fly-wheel 5. It may be desirable that the gear portion 68 mesh with the pinion 26 before the pinion 105 portion 67 meshes with the gear teeth 32, for the reason that, if the pinion portion 67 does not exactly mesh, at first, the same may be rotated by the part 63, through the spring 65, to properly align the teeth and 110 grooves of the parts 67 and 32. Further movement of the pedal 18 will be retarded while the piston 73 is moving over the imperforate portion of the dash-pot cylinder. During this portion of the movement, the 115 parts 62 and 63 may continue their meshing action with parts 32 and 26, respectively. Continued movement of the pedal 18 will cause the piston 73 to uncover the port 79 to allow further unretarded movement of the 120 bell crank lever 41 and its associated parts to move the part 62 into engagement with the abutment 69, in case it is not already there, and to move the part 63 into clutching engagement with the part 62 against the 125 action of the spring 65. The motor M will have had opportunity to attain its full speed during the retarded motion of the pedal and associated parts, there being practically no load on the motor at this time, and when 130

the parts 62 and 63 are engaged, the power of the motor, running at full speed, will be suddenly applied to the crank shaft. Such application of power is highly desirable at 5 times, especially in cold weather, where there is a tendency for grease and moisture, in the cylinder and other parts, to harden and even freeze.

When the engine is started and running 10 under its own power, the one-way clutch 63 prevents the transmission of power from the engine to the motor shaft, thus preventing any damage to the dynamo-electric machine that might result from running at 15 high speed. When it is apparent that the engine is operating under its own power, the pedal 18 is relieved of pressure and the spring 13 engages the clutch 8 with the clutch portion of the fly-wheel 5 and 20 turns the pedal and crank 16 to normal position. The crank 43, being now relieved of pressure, the spring 40 acting through the bell crank lever 41 and rod 42 returns the crank 43 to normal position, the return 25 movement of the piston 73 being unretarded on account of the openings 74 therein. This movement of the bell crank lever 41, due to the spring 40, operates the switch S to connect the machine M as a shunt wound 30 generator, connects the gear 24 to the motor shaft 21 through the clutch 25, thus allowing the engine to drive the machine M through the meshed gears 6 and 24, and disengages the parts 62 and 63 and moves the 35 same out of engagement with the gear teeth 32 and the pinion 26, respectively. Energy from the generator now closes the switch 82 and completes the circuit of the holding magnet 44 to cause the withdrawal of the 40 core extension 45 from the path of the projection 19, thus allowing the subsequent operation of the clutch 8 without interfering with any of the parts of the starting device. When the voltage at the generator 45 terminals is sufficient, the switch 53 is closed, allowing the generator to charge the battery B.

As it is desirable to close the circuit of the magnet 44 only when the engine is operating under its own power, it will be obvious that a circuit direct from the battery 50 may be used for supplying said magnet; and means, directly responsive to the engine speed, may be provided for closing a 55 normally open switch in such supply circuit, when the engine attains a speed corresponding to self-actuation. A means for accomplishing this operation of the apparatus is shown in Fig. 3, wherein all the parts are 60 similar to corresponding parts in Fig. 2, except the operating circuit for the magnet 44 which, instead of being closed in response to the development of sufficient voltage at 65 the terminals of the dynamo-electric machine M, when acting as a generator, is

closed by a speed responsive device associated with the engine. As shown in this figure, the shaft 7 is provided with a centrifugal governor 91, as of the fly-ball type, a sleeve 92, associated with the fly-ball mechanism, being slideable on the shaft 7 to cause a projection on said sleeve to operate an arm 93 which actuates a movable switch member 94 to bridge terminal contacts 95 of a circuit 96, thus closing a circuit including the battery B, circuit wires 84 and 85 and the winding of the magnet 44 and causing retraction of the core extension 45 from the path of the projection 19. It will be apparent that, when the engine ceases to 80 operate at a speed sufficient to maintain the switch 94 in position to bridge the contacts 95, the core extension 45 will be projected into such position as to cause operation of the starting mechanism on the actuation of 85 the clutch operating pedal 18. However, the specific structure and location of the speed responsive device disclosed forms no part of the invention defined by this application. 90

As described generally in connection with the operating circuit of the magnet 44 of Fig. 2, in case the normal circuit-closing means are ineffective to accomplish their intended function, the circuit of the magnet 95 44 may be closed through the normally open switch 86.

It will be obvious that, in accordance with this invention, a starting device is provided that presents no additional control features 100 to the operator, as, for instance, on the dashboard of a vehicle which is provided with such an engine starting device, and, hence, there is no tendency toward the manual operation of the starting device when the engine is operating, and, further, there is no danger of interfering with the starting device, at any time, when the engine is running, for the only control means at hand, namely, the clutch or other operating pedal 105 or arm, is not operatively connected to the actuating means of the starting device, at such time. 110

It is claimed and desired to secure by Letters Patent,—

1. In combination with an engine and its shaft, a second shaft operable through said engine shaft, mechanism for controlling the operation of one of said shafts, starting mechanism for said engine, said starting mechanism being normally ineffective for engine starting purposes, and means normally operative to mechanically associate said controlling mechanism and said engine starting mechanism to permit operation of said starting mechanism through actuation of said controlling mechanism, said associating means being inoperative to permit operation of said starting mechanism through a succeeding actuation of said controlling mech. 130

anism if the speed of the engine is above that corresponding to actuation under its own power.

2. In combination, an engine shaft, a shaft operable by said engine shaft, means for controlling the speed of operation of one shaft relatively to the other, mechanism for starting said engine, and means operable by said controlling means for actuating said starting mechanism, said actuating means being operable to effect actuation of said starting mechanism only when the speed of said engine is below a predetermined value.

3. In combination, an engine, a shaft operable by said engine, means for controlling operation of said shaft by said engine, mechanism for starting said engine, means for operatively associating said controlling means and said engine starting mechanism, said associating means being capable of being rendered inoperative on the completion of the engine starting operation and in response to a speed of the engine above a predetermined value.

25 4. In combination with an engine, a shaft operable by said engine, means for controlling the operation of said shaft by said engine, starting mechanism for said engine, means for actuating said controlling means, and means for operatively connecting said starting mechanism with said actuating means for operation thereby, said connecting means being rendered inoperative subsequent to the release of said actuating means and 35 when the speed of said engine is above a predetermined value.

5. In combination with an internal combustion engine, a shaft driven thereby, a clutch for connecting said engine and said shaft in driving relation, a starter for said engine comprising a motor, and means for simultaneously actuating said clutch and for establishing driving relation between said motor and said engine, said means being automatically rendered inoperative to establish the driving relation between said motor and said engine when said engine is in operation under its own power and said clutch is released.

30 6. In combination, an engine, a load shaft adapted to be driven by said engine, means for connecting said load shaft and said engine in driving relation, means for starting said engine comprising a motor, means within 35 in reach of an operator for actuating said connecting means, and means for establishing driving relation between said motor and said engine, said latter means being actuatable by said operator actuated means only when said load shaft is disconnected from said engine and the speed of said engine is below a predetermined value.

7. In combination, an engine, a shaft adapted to be driven by said engine, means 65 for operatively connecting said shaft to said

engine, means for starting said engine comprising a motor, means within reach of the operator for actuating said connecting means, and means for establishing a driving relation between said motor and said engine, 70 said latter means being normally operatively connected to said operator-actuated means for actuation thereby and being discon-nectible therefrom in response to a speed of said engine above a predetermined value. 75

8. In combination with an engine shaft, a shaft operable thereby, a clutch for connecting said shafts in driving relation, a starter for said engine comprising a motor, power transmitting mechanism between said engine and said motor, and means operative through a single actuation thereof to cause actuation of said clutch and the establishment of driving relation between said motor and said engine, said means being operable 85 to effect its double function of actuating said clutch and establishing driving relation between said motor and said engine only while the speed of said engine is below a pre-determined value. 90

9. In combination, an engine, a work shaft adapted to be driven thereby, a clutch for operatively connecting said engine and said work shaft, a starter for said engine comprising a motor, means for actuating said clutch, a switch in the circuit of said motor, and means for actuating said switch, said switch actuating means being operatively associated with said clutch actuating means at all times when the speed of said engine 100 is below a predetermined value.

10. In combination with an internal combustion engine, a shaft driven thereby, a clutch for connecting said engine and said shaft in driving relation, a starting device 105 for said engine, and mechanism for establishing driving relation between said starting device and said engine, said clutch and said mechanism being operatively associated for dependent operation when said engine 110 is at rest and said clutch being capable of independent operation only when said engine is running at a speed above a predetermined value.

11. In combination, an engine, a shaft operable thereby, mechanism for controlling the operation of said shaft by said engine, a starter for said engine comprising a motor, power transmitting mechanism between said engine and said motor, a switch for 115 closing the operating circuit of said motor, and means operable to actuate said controlling mechanism and to operate said switch and render said power transmitting mechanism operative to cause the motor to drive said engine, said means being operative to accomplish its triple function only when the speed of the engine is below a predetermined value. 120

12. In combination, an engine, a starter 1

therefor comprising a motor, power transmitting mechanism between said engine and said motor comprising two members adapted to be operatively connected to said motor

5 and engine, respectively, and to each other, a switch in said motor circuit, and means for successively closing said motor circuit, operatively connecting said members to said motor and said engine, respectively, and operatively connecting said members together.

13. In combination, an engine, a load adapted to be driven thereby, means adapted to connect said engine in driving relation to the load, a starter for said engine comprising a motor, power transmitting mechanism between said engine and said motor comprising two members adapted to be operatively connected to said motor and said engine, respectively, and to each other, a switch in said motor circuit, and means for successively closing said motor circuit and for rendering said power transmitting mechanism operative to cause said motor to

25 drive said engine.

14. In combination, an engine, a work shaft adapted to be driven thereby, a clutch for operatively connecting said engine and said work shaft, a starter for said engine comprising a motor, power transmitting mechanism between said engine and said motor comprising two members adapted to be operatively connected to said motor and engine, respectively, and to each other, a switch in said motor circuit, and means for actuating said clutch and for successively operating said switch to close said motor circuit, operatively connecting said members to said motor and engine, respectively, and operatively connecting said two members together.

15. In combination, an engine, a shaft operable by said engine, means for controlling operation of said shaft by said engine, mechanism for starting said engine, means for operatively associating said controlling means and said starting mechanism, said controlling means and said starting mechanism being rendered operative solely through actuation of said controlling means when the speed of operation of said engine is below a predetermined value, and the operativeness of said associating means for caus-

ing operation of said starting mechanism being dependent upon the speed of said engine.

16. In combination, an engine shaft, a second shaft operable by said engine shaft, mechanism for controlling the operation of said second shaft by said engine shaft, mechanism for starting said engine, said starting mechanism being normally inoperative for engine starting purposes, mechanism for operatively associating said starting mechanism with said control mechanism to effect operation of said starting mechanism through actuation of said control mechanism, and means automatically operative through a succeeding operation of said controlling mechanism to render said associating means inoperative when the speed of one of said shafts is above a predetermined value.

17. In combination, an engine, a starter therefor comprising a motor, power transmitting mechanism between said engine and said motor comprising two members adapted to be operatively connected to said motor and said engine, respectively, and to each other, and means for successively operating connecting said members to said motor and said engine, respectively, and operatively connecting said members to each other.

18. In combination, an engine and its shaft, a second shaft operable by said engine shaft, means operative to control the operation of one of said shafts, a motor for starting said engine, power transmitting mechanism between said motor and said engine, said power transmitting mechanism being normally in inoperative condition, means for actuating said controlling means and for rendering said power transmitting mechanism operative, said actuating means comprising two relatively movable elements, and a device for operatively connecting said two elements, and means responsive to the speed of said engine for rendering said connecting device inoperative.

In testimony whereof, the signature of the inventor is affixed hereto in the presence of two witnesses.

JOHN J. KANE.
